UNITED STATES PATENT OFFICE.

WILLIAM PERRY TAYLOR, OF BUFFALO, NEW YORK.

BRAKE-SHOE.

SPECIFICATION forming part of Letters Patent No. 783,087, dated February 21, 1905.

Application filed November 17, 1904. Serial No. 233,102.

To all whom it may concern:

Be it known that I, WILLIAM PERRY TAYLOR, a citizen of the United States, and a resident of Buffalo, in the county of Erie and State of New York, have invented certain new and useful Improvements in Brake-Shoes, of which the following is a specification.

This invention relates to that class of brake-shoes used on railway cars or locomotives, which are of a curved form and adapted to frictionally contact with the wheel-surface, and particularly to shoes constructed in one piece.

The invention essentially comprises a body which is cast complete in one piece with a reinforcing element therein entirely surrounded and gripped throughout by the contraction of the metal of said body in cooling, whereby the opposed surfaces of the metal body and reinforcing element are in contact continuously throughout and unite to form a solid homogeneous reinforced shoe.

One of the specific features of the invention has reference to one or more strengthening-rods which extend longitudinally through the cast shoe-body near the outer surface or back thereof, but entirely beneath the surface, being completely surrounded and gripped by the cast metal of the shoe-body throughout their length.

Another feature consists in roughening the surface of the rods, so that it will be more rigidly and strongly held in the cast body, thereby forming a more intimate alliance between the two metals of the shoe-body and rods and producing a practically homogeneous reinforced shoe.

The principal object of the invention is to strengthen the cast body of the shoe throughout by rods or other reinforcing means, which are entirely surrounded and rigidly gripped throughout on all sides by the contraction of the shoe-body in cooling.

Other features and advantages and objects will be hereinafter described and perhaps claimed, reference being had to the accompanying drawings and the following description.

Figure 1 is a longitudinal section through the brake-shoe on line *a a*, Fig. 7. Fig. 2 is a detached view of one of the strengthening-rods. Fig. 3 is a longitudinal section through the brake-shoe on line *b b*, Fig. 1, the strengthening-rods being shown in full. Fig. 4 is a longitudinal section through the brake-shoe on line *c c*, Fig. 9, showing another form of strengthening-rod. Fig. 5 is a detached view of the other form of strengthening-rod. Fig. 6 is a longitudinal section through the brake-shoe on line *d d*, Fig. 4. Fig. 7 is an end elevation of the brake-shoe shown in Figs. 1 and 3. Fig. 8 is a transverse section through the brake-shoe on line *e e*, Fig. 1. Fig. 9 is a section through the brake-shoe on line *f f*, Fig. 4. Fig. 10 is a section through the brake-shoe on line *g g*, Fig. 4. Fig. 11 is a detached end view of the form of strengthening-rod shown in Figs. 4, 5, and 6. Fig. 12 is a transverse section through the strengthening-rod on line *h h*, Fig. 5.

In referring to the drawings for the details of construction like numerals designate like parts.

The principal disadvantage with brake-shoes which are provided with reinforced backs is that the reinforcing-plate is not secured or fastened firmly enough to the shoe-body to hold a portion broken therefrom from detaching itself and falling.

In my improved construction I use one or more rods, preferably two, instead of a plate around which the metal of the shoe-body is cast complete at one operation and in one piece, so as to entirely surround the rods, which are firmly gripped continuously throughout their length within the body by the contracting of the metal in cooling.

In the adaptation shown in Figs. 1, 2, 3, 7, and 8 two rods 1 are used which are curved to the curvature of a brake-shoe body 2 and extend longitudinally throughout the shoe-body from end to end thereof, being embedded and completely surrounded by the cast metal of the said body 2. To still further increase the securing of the rods in the cast body, they may be roughened, as shown at 3, there-

by providing on the peripheries of the rods a number of minute recesses, into which the cast metal will extend, and a number of minute projections, which will embed themselves in 5 the surrounding portions of the cast body and produce an interlocking of the contacting surfaces of the rods and cast brake-body.

The rods 1 preferably are two in number and extend parallel to each other, each extending 10 throughout one of the upper corners of the brake-shoe body, and are preferably of circular or equivalent shape in cross-section.

In order to produce a more perfect alliance 15 between the surface of the rods and the surrounding surface of the cast body, the rods are first heated before being placed in the mold and the molten metal poured around them after they are placed in their proper position.

20 In cooling the cast metal contracts and grips the rods continuously throughout their length upon all sides, thus forming a most intimate contact between the two metals and practically producing a homogeneous reinforced brake-shoe.

25 In the adaptation shown in Figs. 4, 5, 6, 9, 10, 11, and 12 the ends of the rods are joined to form a loop 4, which is entirely within the cast-metal body and has its ends 5 bent at an 30 angle and extended into the end abutments 6 of the brake-shoe body to reinforce and strengthen said abutments and also more securely anchor the loop in place. The surface of the loop 4 may be roughened; as shown at 7, 35 if desired.

The term "reinforcing-rod" is used in the specification to differentiate from the reinforcing-plates previously used in the art and which were nearly as broad as the body of the brake- 40 shoe itself, and it is to be understood that by the said expression "reinforcing-rod" I mean an element either formed of one single piece throughout or formed of a plurality of mutually-connected pieces which are comparatively narrow in width relatively to the brake-shoe body, whereby no broad surface is presented to the molten cast metal, so that the opposed surfaces of the two metals are in intimate contact and practically joined throughout.

50 The great advantage of this improved shoe is the rigid fastening and gripping of the rods within the cast-metal body, which produces a stronger and better-wearing shoe that is less liable to break under abnormal stress and which will wear closer than the ordinary shoe, the shoe being good practically until worn down to expose the rods.

55 By casting the metal-body complete in one piece and entirely around the rods, which are preferably of wrought-iron or steel, a brake-shoe is produced which is for all essential purposes practically homogeneous, the contrac-

tion of the cast body upon the rods anchoring them so rigidly in place and producing such 65 an intimate contact between the surfaces that it may be fairly said that they unite and form practically a solid reinforced one-piece brake-shoe.

It will be noted that in this improved shoe 70 the rods or other reinforcing means are unsupported except by the metal of the body, which is cast complete in one piece and entirely surrounds the reinforcing means on all sides throughout.

75 I claim as my invention—

1. A solid homogeneous reinforced brake-shoe comprising a metal body cast complete in one piece and a rod extending through said body and gripped throughout on all sides by 80 the contraction of the cast body in cooling.

2. A solid homogeneous reinforced brake-shoe comprising a metal body cast complete in one piece and a rod extending longitudinally throughout and entirely beneath the 85 surface of said body and gripped throughout on all sides by the contraction of the cast body in cooling.

3. A brake-shoe comprising a metal body cast complete in one piece and a roughened- 90 surface rod extending through said body and gripped on all sides by the contraction of the cast body in cooling.

4. A solid homogeneous reinforced brake-shoe comprising a metal body cast complete 95 in one piece and a reinforcing means, including at least in part two parallel rods extending longitudinally through the opposite upper corners of the cast body and entirely beneath the surface of and surrounded and gripped on all sides throughout by the contraction of the cast metal of said body in cooling.

5. A brake-shoe comprising a metal body cast complete in one piece and a reinforcing means, including at least in part two parallel 100 roughened-surface rods extending longitudinally through the opposite upper corners of the cast body and entirely beneath the surface of and surrounded by the cast metal of said body.

6. In a solid homogeneous reinforced brake-shoe, a reinforcing means including at least in part a rod, and a body cast complete in one piece entirely around and gripping said rod throughout on all sides.

7. A brake-shoe comprising a body cast complete in one piece with a reinforcing-rod therein entirely surrounded and gripped throughout by the contraction of the metal of said body in cooling, whereby the opposed surfaces of the metal body and the reinforcing element are in contact continuously throughout and practically unite to form a solid homogeneous reinforced shoe, substantially as set forth.

8. A brake-shoe comprising a body cast complete in one piece with a reinforcing element

therein; said element being comparatively narrow in width and entirely surrounded and gripped throughout by the contraction of the metal of said body in cooling, whereby the opposed surfaces of the metal body and the reinforcing element are in contact continuously throughout and practically unite to form a solid homogeneous reinforced shoe, substantially as set forth.
